UNITED STATES PATENT OFFICE.

HARRY W. LOCKLEY, OF NEW CASTLE, PENNSYLVANIA.

BROACHING-PRESS.

1,218,426.

Specification of Letters Patent.

Patented Mar. 6, 1917.

Application filed August 11, 1916. Serial No. 114,444.

To all whom it may concern:

Be it known that I, HARRY W. LOCKLEY, a citizen of the United States, residing at New Castle, in the county of Lawrence and State 5 of Pennsylvania, have invented certain new and useful Improvements in Broaching-Presses; and I do declare the following to be a full, clear, and exact description of the invention, such as will enable others skilled 10 in the art to which it appertains to make and use the same.

My invention which has reference broadly to improvements in broaching presses relates more particularly to those designed for accurately 15 finishing the bores of bronze and brass bushings. Heretofore, presses of this character have been almost universally provided with clutches controlled by foot pedals and by means of these pedals the 20 working head has been stopped after each broach has been forced through a bushing, and while said head remains in this idle position, an additional bushing and broach have been inserted beneath it, whereupon 25 by actuation of the foot pedal said head is again brought down. This method has been found to require considerable time since the press cannot work at its maximum capacity due to the fact that it is successively stopped 30 and started.

It is the object of the present invention to so improve upon broaching presses as to permit the working heads thereof to reciprocate continuously and to provide simple means 35 for automatically feeding the bushings from a work holder in which they are placed by hand into another holder disposed under the aforesaid head. By these improvements, from four to seven times the amount of 40 work turned out by the present day methods may be accomplished.

With the foregoing general object in view, the invention resides in certain novel features of construction, and in unique combinations 45 of parts to be hereinafter fully described and claimed, the descriptive matter being supplemented by the accompanying drawings which constitute a part of this application and in which:

50 Figure 1 is a side elevation of a broaching press equipped with the improved features of construction;

Fig. 2 is a top plan view of the table and the parts carried thereby;

55 Fig. 3 is an end elevation of the parts shown in Fig. 2;

Figs. 4, 5 and 6 are vertical transverse sections on the planes of the lines 4—4, 5—5 and 6—6 of Fig. 2;

Fig. 7 is a longitudinal section on the 60 plane of the line 7—7 of Fig. 2 showing one broach and bushing in position for the former to be forced through the latter by the working head and illustrating another bushing and broach supported by the reciprocating 65 feed member;

Fig. 8 is a view similar to Fig. 7 showing one broaching tool forced substantially through a bushing and disclosing the other 70 tool and bushing in position to be fed beneath the work head by the proceeding stroke of the reciprocating member;

Fig. 9 is a horizontal section taken substantially on the plane of the line 9—9 of 75 Fig. 3;

Fig. 10 is a plan view of the reciprocating feed member.

In specifically describing the structure shown in the drawings above briefly described, similar characters will be employed 80 to designate corresponding parts throughout the several views and reference will be herein made to the numerous elements by their respective indices. To this end, the numeral 1 designates a suitable base from 85 which the usual standards 2 rise, said standards supporting at their upper ends a crank shaft 3 which is driven by means of suitable gearing from a main power wheel 4. An electric motor 5 is preferably provided for 90 driving the wheel 4, the two being connected by means of a belt 6, and the speed of said motor and therefore the speed of the entire machine, may be regulated at will by a suitable rheostat 7. A common type of vertically moving working head or ram 8 is operated continuously from the crank shaft 3, being connected therewith by a pitman 9. For discontinuing movement of the working head 8 for any reason without stopping 100 the motor 5, the standard clutch (not shown) is employed for connecting the crank shaft 3 with the driving means thereof, said clutch being controlled by the usual foot pedal which is illustrated conventionally at P in 105 Fig. 1. This pedal and clutch referred to are standard equipment and will for the most part be used only when setting or adjusting the machine or making a quick stop.

The parts so far briefly described are of 110 well known formation and the construction thereof constitutes no part of the present in-

vention, although the details of the latter coöperate with the parts of the press to which reference has been made.

- Mounted on a suitable rectangular frame 10 spaced below the head 8 and secured to said frame by bolts or the like 11 is a horizontal rectangular table 12 upon which the improved features of construction are mounted. At approximately its center the table 12 is provided with a vertical opening 13 whose upper end is enlarged and receives therein a work supporting ring 14 whose upper edge lies flush with the upper surface of the table 12.
- 15 A relatively fixed angle metal guide bar 15 extends across the table 12 from the rear edge of said table toward the front edge thereof, the horizontal flange of said guide having transverse slots 16 through which 20 machine screws 17 pass to secure the guide adjustably in place. The guide 15 as shown clearly in Fig. 6, is disposed above one edge of the work supporting ring 14, while disposed above the opposite edge thereof in 25 spaced parallel relation with said guide 15 is a second guide bar 18, the lower edge of the latter being provided with laterally extending flanges 19 which rest slidably on the table 12 beneath a bar 20 which is secured 30 in place by machine screws or the like 21. An abutment bar 22 is adjustably secured by bolts 23 and slots 24 to the table 12 and is spaced outwardly from the guide bar 18, coil springs 25 being interposed between said bars 18 and 22 whereby the former will be yieldably forced toward the bar 15, the utility of this structure being herein-after described.

In substantial alinement with the bar 15 40 and extending from the horizontal flange thereof through the front edge of the table 12 is a groove 26 formed in the upper face of said table, said groove receiving slidably therein a block 27 shown in detail in Fig. 45 10, this block being connected by means of an integral arm 28 with a feed member 29 in the form of a rectangular head equal in height to the bars 15 and 18, the rear end of said head having a V-shaped vertically 50 extending groove 30. A guide plate 31 is secured to the table and overlies the block 27 and arm 28, said plate having therein a longitudinally extending slot 32 through which a vertically disposed stud 33 extends, 55 said stud being threaded into the block 27 while the upper end thereof is provided with a head 34.

The front end of a horizontal rod 35 is pivoted by means of a bolt or the like 36 to 60 the head 34, the rear end of this rod being pivoted to the upper end of a bell crank lever 37 fulcrumed to one of the standards 2, the other end of said lever being pivoted to the lower section of an expandible and 65 tractible pitman rod 38 which at 39 is con-

nected eccentrically with a disk 40 on the crank shaft 3. It will thus be evident that as this shaft is rotated, the rod 38 will reciprocate vertically and that the bell crank 37 will transfer this motion to move the rod 35 horizontally, thus causing the feed member 29 to alternately proceed toward the rear of the table 12 and recede toward the front edge thereof. In a manner to be described, this proceeding and receding movement of the member 29 serves to successively position unfinished bushings on the ring 14 in which position a broaching tool is forced therethrough by downward movement of the working head 8.

80 A work holder 42 is disposed at and in a plane above the front ends of the guide bars 15 and 18, said holder comprising briefly a pair of jaws 43 and 44, the former adjustably secured by means of bolts 45 to the table 12 and preferably having a rib 46 traveling in a transverse groove 47 in the upper side of said table. The jaw 44 is provided on its lower side with a rib 48 received slidably in a transverse groove 49 90 in the upper side of table 12. The body portion of the jaw 44 is slidably mounted in a suitable guide 50 which is secured to the table 12, a spring 51 being interposed between this guide and the jaw proper as 95 shown clearly in Figs. 2, 3 and 4. A set screw 52 is threaded through an ear 53 rising from the outer end of the jaw 44 and by tightening or loosening this screw, it will be seen that the active face of said member 100 44 may be correctly spaced from 43.

In operation, the motor 5 will be driven at the proper speed, which speed is under the control of the rheostat 7, and said motor, through the driving connections described 105 will reciprocate the working head 8 and the feed member 29 in timed relation, said head being moved downwardly as soon as member 29 is moved to the limit of its rearward stroke. The bushings B are placed in the work holder 42 one at a time when the feed member 29 is at or near the limit of its rearward movement (Figs. 2 and 7), said bushings resting on said member 29, a broaching tool T having been previously inserted in 110 the bushing as will be clear from Figs. 7 and 8. As the feed member 29 now recedes from the position shown in Fig. 7 to that depicted in Fig. 8, the bushing which has been previously supported thereon will drop 115 by gravity to the table 12. When member 29 now moves again rearwardly the bushing and tool will be positioned beneath the working head or ram 8, and as the latter now moves downwardly, said tool is forced through the bushing and will be deposited into a box or the like not shown. While this is taking place, the operator places another unfinished bushing and a tool applied thereto within the work holder 42 and as 120 125 130

this bushing is fed rearwardly upon the next rearward stroke of the feed member 29 it forces the finished bushing rearwardly between the guide bars 15 and 18. Both of 5 these bars are formed on their inner opposed faces with vertical grooves 54 which, due to the coil springs 25, yieldably grip the bushings to retain them in operative position on the ring 14 while the broach is being 10 forced therethrough. When the next bushing is forced rearwardly the springs 25 yield and thus permit the finished bushing to move toward the rear end of the machine at which all of the bushings are discharged 15 after the broaching process. To prevent unnecessary binding of the bushings between the rear ends of the bars 15 and 18, the latter is preferably decreased in thickness in rear of its groove 54 as indicated 20 at 55.

In case the operator should insert a bushing into the work holder 42 as one end of the feed member 29 is moving across the lower end of said holder, no serious accident will 25 occur since the spring 51 will yield outwardly and will thus allow said member 29 to force the bushing free of the holder.

By constructing the machine to operate in the manner above described, much more 30 work can be accomplished since it operates continuously rather than intermittently as is the case with most broaching presses now in use. It has been found that from four to seven times as many bushings may be 35 broached in a day by the improved machine as can be finished by the machines now being employed for this purpose.

In the foregoing, I have described certain specific details of construction for accomplishing probably the best results and 40 due to the fact that the machine operates to great advantage when manufactured in this manner, the organization of parts shown and described constitutes the preferred 45 form of my machine. It is to be understood, however, that within the scope of the invention as claimed, numerous changes may be made without sacrificing the main advantages thereof. The machine is not limited 50 to broaching bushings or to a hand feed since it is obvious that it may be used for other purposes and that any suitable mechanical or gravity feed may be used.

I claim:

55 1. In a broaching press, the combination of a work holder for retaining bushings in place while the broaching process is being performed, a non-rotating proceeding and receding feed member for feeding bushings 60 to said holder, and a second work holder over the feed member for retaining the unfinished bushings in upright position on said feed member during the receding strokes thereof, said feed member and second work holder permitting said bushings

to drop by gravity onto the proceeding path of the former at the completion of said receding strokes, said second holder being immovable when the machine is properly operating but being expansible transversely of 70 the line of travel of the feed member to prevent injury to the bushings or machine in case one of the former should bind in said holder.

2. In a broaching press, the combination 75 of a table, a work holder for retaining bushings in place while the broaching process is being performed, a non-rotating proceeding and receding feed member movable toward and away from said work 80 holder for feeding the bushings thereto, and a second work holder above said feed member for retaining the unfinished bushings in upright position on said feed member upon the receding strokes of the latter, said 85 member permitting the bushings to drop by gravity onto its proceeding path at the completion of its receding strokes; said second work holder consisting of a relatively fixed jaw adjacent one side of the feed 90 member, a guide secured to said table at the other side of said member, a second jaw in said guide and slidable transversely of the line of movement of the feed member, and spring means for holding said second jaw in 95 operative position, said second jaw being immovable when the machine is properly operating but being adapted to yield outwardly in case a bushing should bind in said 100 second work holder.

3. A broaching press comprising a holder in which bushings or the like are adapted to be held while the broaching process is being performed, said holder comprising a horizontal support, a fixed horizontal bar extending along the upper side of said support, a movable horizontal bar parallel with and spaced horizontally from the fixed bar, and spring means for forcing the movable bar toward the fixed bar to grip the bushings 105 while being and for a limited time after being broached, the inner opposed faces of said bars having seats to engage opposite portions of said bushings while the broaching process is being performed in combination with means for feeding the bushings 110 into the holder.

4. A broaching press comprising a holder in which bushings or the like are adapted to be held while the broaching process is 115 being performed, said holder comprising a horizontal support, a fixed bar extending along the upper side thereof, a relatively movable bar parallel with and spaced horizontally from said fixed bar, outwardly projecting flanges on the lower edge of said movable bar, a guide bar overlying said flanges and secured to the support, a second fixed bar spaced outwardly from said guide 120 bar, and springs interposed between said 125 guide bar and the second fixed bar.

1
second fixed bar and the movable bar for forcing the latter toward the first fixed bar to grip the bushings between the two while being and for a limited time after being broached; in combination with means for feeding the bushings into the space between the first named fixed bar and the movable bar.

5. A broaching press comprising a work holder in which bushings or the like are adapted to be held while the broaching process is being performed, a non-rotating proceeding and receding feed member for feeding the bushings to said holder, said feed member having a flat straight upper side, and a horizontal table upon which said holder is mounted and adjacent the upper side of which said feed member operates; in combination with a second work holder comprising a pair of jaws secured to the aforesaid table on opposite sides of the feed member and extending to spaced points above said feed member, said jaws serving to loosely hold therebetween the bushings to permit them to rest on said flat side of the feed member during its receding strokes and to drop in advance of said feed member on the proceeding strokes thereof.

6. In a broaching press, the combination of a horizontal table, a proceeding and receding feed member mounted slidably on said table, an operating rod connected with said member, a pair of horizontal guide bars resting on said table on opposite sides of and extending beyond said feed member, means for permitting one of said bars to move toward the other, spring means for so moving said one bar, both bars having transverse grooves in their inner faces to receive the bushings while the broaching process is being performed, and a work holder above the feed member to receive the bushings, said feed member moving beyond said work holder on its receding strokes to permit the bushings therein to drop onto

the table in advance of said feed member to be forced into the aforesaid grooves by the proceeding strokes thereof.

7. In a broaching press, the combination of a horizontal table, a proceeding and receding feed member mounted slidably on said table, an operating rod connected with said member, a pair of horizontal guide bars resting on said table on opposite sides of and extending beyond said feed member, means for permitting one of said bars to move toward the other, spring means for so moving said one bar, both bars having transverse grooves in their inner faces to receive the bushings while the broaching process is being performed, an angular jaw having one end disposed above the feed member and its other end secured to the table at one side of the feed member, a guide secured to said table at the other side of said member, a second angular jaw received slidably in said guide and having one end disposed over the feed member for co-operation with the corresponding end of the first jaw, both of said jaws having vertically extending grooves to loosely receive the bushings to be broached, and a spring interposed between the second named jaw and the guide thereof for normally forcing this jaw inwardly but for permitting it to yield outwardly in case of accident, the aforesaid feed member moving beyond the two jaws on its receding strokes to permit the bushings held by said jaws to drop onto the table in advance of said feed member to be forced by the latter into the grooves of the aforesaid bars.

In testimony whereof I have hereunto set my hand in the presence of two subscribing witnesses.

HARRY W. LOCKLEY.
